UNITED STATES PATENT OFFICE.

GUSTAV SCHKOMMODAU, OF NUREMBERG, GERMANY, ASSIGNOR TO THE FIRM OF RICHARD BRASS, OF NUREMBERG, GERMANY.

TEMPLET-CUTTER GUIDE FOR MACHINE-TOOLS.

SPECIFICATION forming part of Letters Patent No. 687,699, dated November 26, 1901.

Application filed July 8, 1901. Serial No. 67,500. (No model.)

To all whom it may concern:

Be it known that I, GUSTAV SCHKOMMODAU, a subject of the King of Prussia, German Emperor, and a resident of Nuremberg, Bavaria, 5 in the Empire of Germany, have invented certain new and useful Improvements in Templet-Cutter Guides for Machine-Tools, of which the following is a specification.

The present invention relates to a templet- 10 cutter guide for lathes and other machine-tools; and it consists of the details of construction hereinafter set forth, and particularly pointed out in the claims.

In order to render the present specification 15 easily intelligible, reference is had to the accompanying drawings, in which similar characters of reference denote similar parts throughout the several views.

Figures 1 to 5 show one form of embodying 20 the invention, Fig. 1 being a cross-section through a compound tool-slide, Fig. 2 a detail sectional elevation of a modification, Fig. 3 a longitudinal section through the same tool-slide, Fig. 4 a central section through 25 the part of the slide engaging the transport-spindle, and Fig. 5 a plan view of the slide. Figs. 6 to 8 show another form of embodying the invention, Fig. 6 being a part cross-section through the tool-holding slide, Fig. 30 7 a longitudinal section, and Fig. 8 a plan. Figs. 9 to 12 show a further modification, Fig. 9 being a part cross-section through the compound slide, Fig. 10 a section of a detail, Fig. 11 a longitudinal section through the 35 slide, and Fig. 12 a plan of the same.

Referring to Figs. 1 to 5, at the back of the lathe-bed *b* a flange or holder *d* is provided, to the upper part of which the templet *e* is secured. This templet represents the form it is 40 desired to impart (in profile) to the article being turned or otherwise shaped or planed. The main slide *n* slides, as usual, on the bed *b*, and the transverse slide or tool-holder *m* is guided transversely to the main slide *n* on the 45 guide *o*, slide *n* running on guides *c*. The main slide *n* does not fit immediately onto the transport-spindle *x*, as is usual; but an intermediate sleeve *w* is provided and adapted to be moved by the said spindle, said sleeve being 50 slidable but not rotatable in a housing *w'*, which is formed on the slide *n*. The sleeve *w*

is provided with a rack *v* in, which a pinion *t* engages, which is mounted in the housing *w'* and is wider than the said rack *v*, so that when the rack is in engagement with the lower part of the said pinion a second rack *s*, 55 mounted on the transverse slide *m*, will be in engagement with its upper part, the two racks lying at right angles one to the other. To the slide *n* is further attached a weight *2*, 60 fast to the end of a cord *1*, guided over a suitable roll, Fig. 3. This weight has a tendency to pull the pinion *t* along the rack *v*. The slide *m* is provided with the finger *r*, rigidly attached thereto and which is kept in engagement with the templet *e* by the action of the weight *2* on the pinion *t*, and consequently 65 on the two racks *v* and *s*.

The device operates in the following manner: When the spindle *x* is turned, (automatically or by hand,) it moves the whole of the compound slide *m* along the bed of the lathe, and by the action of the weight *2* the pinion will thus be turned by the rack *v*, so that it will operate the upper slide *m* to continually keep the finger *r* against the templet *e*, and thus the cutter *h*, which is mounted on the slide *m* in the usual manner, will be moved along, the article being turned in a line corresponding to the shape of the templet, and the article will be automatically 75 turned to the profile of the templet. 80

In Fig. 2 instead of the screw-spindle a worm-spindle *x'* is provided, which engages a worm-wheel *u'* of the pinion *t*, said worm-wheel being rigidly connected to the said spindle, so that on turning the spindle the slide *m* will be moved by the pinion *t*. 85

In Figs. 6 to 8 the top of the sleeve *v'* is provided with slanting teeth which engage corresponding teeth or racks *s'* formed at the bottom of the slide *m'*, the weight *2'* in this case also acting on the slide *n'*, and the slanting teeth of the two parts tending, under the influence of the said weight, to keep the finger of the slide *m'* against the templet *e'*, as will be readily understood from the foregoing 90 description. 95

In Figs. 9 to 11 the rack *v''* is turned upwardly and engages a pinion *7*, fast on a screw-spindle *8*, which is mounted in the upper part of the slide *n''* and with which an 100

internally-threaded nut 9, in engagement with the slide m'' , engages, so that when the spindle-pinion 7 is turned by the action of the rack v'' the slide m'' will also be kept with its finger r'' against the templet e'' . In Fig. 10 a worm 10 and worm-wheel are substituted for the pinion 7.

The automatic guide device may also be employed in connection with planing-machines and shaping-machines, and particularly for machines for cutting the profile of teeth. When the device is employed for shaping-machines, the shaping-tool is attached to the slide m instead of the cutter h and is rotated by any suitable mechanism.

I claim—

1. In a machine-tool having a compound tool-carrying slide the combination of a templet fixed at the rear of the slide, a finger on the upper member of the said slide, to contact with the said templet, a spindle to operate the slide along its bed, a sleeve on said spindle, fixed in the lower member of the slide and having a rack, and a rack attached to the upper member of the said slide, a pinion mounted in the lower member of the said

slide and engaging both the said racks and a weight suspended from the lower member of the slide and adapted to pull the same against the action of the transport-spindle substantially as described.

2. In a machine-tool having a compound tool-carrying slide, the combination of a templet attached at the rear of the said slide, a finger on the upper member to contact with the said templet, a transport-spindle for the said slide, a sleeve on the said spindle having a rack, a rack on the upper member of the said slide and a pinion on the lower slide member to engage both the said racks, and means for exercising a pull on the lower slide member in a direction opposite to that of motion of the slide along its bed in the manner and for the purpose substantially as described.

In witness whereof I have hereunto set my hand in presence of two witnesses.

GUSTAV SCHKOMMODAU.

Witnesses:

ANDREAS STICH,
OSCAR BOCK.
